DISTILLATION OF HYDROCARBON OILS

Marvin C. Rogers, Chicago, Ill., assignor to Standard Oil Company (Indiana), Chicago, Ill., a corporation of Indiana

Application December 20, 1933, Serial No. 703,190

3 Claims. (Cl. 196—65)

This invention relates in general to improvements in the art of hydrocarbon oil distillation and more especially to a method of producing a maximum yield of clean pressure still charging stock from heavier portions of crude oil with the production of certain quantities of coke and gasoline as valuable by-products. The expression "clean pressure still charging stock" is intended to mean a stock which when cracked by any suitable method does not form any appreciable portion of objectionable coke.

Various methods have been employed in the production of reasonably clean charging stock from the heavier portions of crude oil. One method is an ordinary coking distillation in direct fired batch stills which produces a high yield of clean charging stock but which is quite expensive to operate, the labor and fuel costs being very high. Another method is a non-cracking distillation effected with the aid of steam or vacuum which assists in carrying over the heavier distillates from the heavier portions of the crude oil. In employing this method, care has to be exercised to avoid carrying the stock down to a heavy bottom as otherwise a rather dirty charging stock would be obtained which, to be heavily cracked without excessive coke formation, would have to be mixed with large quantities of clean charging stock.

In carrying out the present process, crude oil may be subjected to a non-cracking distillation to produce a residue which may be highly viscous or substantially solid at ordinary temperatures and free from oils of the gas oil boiling range as well as lower boiling oils. The initial distillation of the crude oil may be carried out by any suitable method and the extent to which this distillation is carried out may be varied depending upon the particular crude being treated and other requirements of the process.

The residuum thus obtained from the non-cracking distillation is passed through a heating coil in a heating zone wherein it is raised to a temperature suitable to be coked in an enlarged chamber by its contained heat, the vaporous constituents from the enlarged chamber being fractionated to obtain the desired clean charging stock and gasoline. In accordance with my invention the temperature of the heated residuum before entering the coking zone is increased to a value higher than that attainable in the heating zone. Heretofore the temperature of the residuum could not satisfactorily be raised above certain critical ranges as objectionable coke deposition would occur in the heating coil thereby

shortening the length of any particular run by the clogging up of the heating coil. My invention permits of an increase in heat supply to the residuum before it enters the coking zone which is not now possible or practical in commonly used methods. The increase in heat supplied to the residuum enables an operator to not only obtain a maximum yield of pressure still charging stock of the desired cleanliness from the residuum but to also improve the quality of the coke and gasoline produced in the process as valuable by-products.

My invention will be clearly understood from the following description in conjunction with the accompanying drawing which illustrates a diagrammatic view of apparatus suitable for carrying out the invention.

Referring to the accompanying drawing, the numeral 1 indicates a source of supply of hot petroleum residue for carrying out my process. The source of supply of hot petroleum residue may be the last of a series of continuous stills or may be the flash drum of a pipe still or other convenient sources of hot heavy residue from crude oil. This residue should preferably be of the type subjected to but little cracking or decomposition. The hot residue may be withdrawn through a line 2 by means of a pump 3 and forced through a line 4 to a heating coil 6 positioned in a suitable furnace 5, the heat for which is preferably supplied by radiation from the products of combustion produced by a suitable burner or burners 7. If difficulty is experienced in pumping the hot residue from the source of supply 1 to the heating coil 6, a cooler (not shown) may be provided before the oil reaches the pump 3 in order to slightly reduce its temperature to a point where satisfactory pumping may be effected.

The petroleum residue passing through the heating coil 6 is raised to a suitable coking temperature therein and passed through a valved transfer line 8 to a manifold 9 having a plurality of valve pipes 11 connecting it with an enlarged coking chamber 12, which may be suitably insulated against loss of heat. The coking chamber 12 is preferably vertical and of substantial dimensions and is adapted to contain the heated residue while distillation to coke takes place. The coking chamber 12 may be provided at its upper end with a valved pipe 13 which opens to the atmosphere. Vaporous constituents evolved in the coking chamber 12 rise upwardly therein and are conducted by means of a valved line 14 into the base of a suitable fractionating column 15. The

fractionating column 15 may be of any desired type, for instance a bubble tower provided with suitable bubble trays or plates. Suitable means may also be provided (not shown) for supplying a refluxing medium into the fractionating column 15. The vaporous constituents leaving the fractionating column 15 may be conducted through a line 16 to a suitable condenser 17 of any desired type. The condenser is connected with a distillate receiver 19 by means of a pipe 18, the distillate receiver having a valved gas outlet 21 at its upper end and a valved liquid drawoff line 22 at its bottom.

Only one coking chamber 12 has been illustrated for carrying out my invention. It is to be clearly understood that several of these chambers may be used, preferably three in number. The oil passing through the transfer line 8 may enter any selected one of these chambers through suitable manifolds and connecting pipes similar to those shown. The manifolds may be connected to the line 8 and heated residue caused to flow to the selected coking chamber by manipulation of suitable valves. The use of several chambers enables the process to be carried out for a long period by changing the flow to the next chamber when one has been filled with coke.

The coking chamber 12 may be provided at its top with a valved pipe 23 which may extend to a suitable manifold, not shown, which connects with each of the manifolds associated with the coking chambers. By this arrangement, vapors from the coking chamber 12, or a part of the vapors may be passed through another empty chamber thereby preheating it for the reception of heated residue to be distilled to coke. The vapors after passing through the coking chamber next to be used may be passed through the line 14 to the bottom of the fractionating column 15. No claim is made to the method of preheating the coking chamber next to be used as it is described and claimed in the application of Ernest W. Thiele, Serial No. 332,541, filed January 14, 1929, now U. S. Patent 1,947,319.

As is clearly shown in the drawing, the valved pipes 11 associated with the coking chamber 12 permit the residue to enter the chamber at various levels. The lowest pipe may be so placed as to cause the residue to enter the coking chamber 12 at the base thereof.

The coking chamber 12 is preferably mounted in an elevated position on any suitable supporting structure and is provided with a removable closure 24. The closure 24 permits entry into the coking chamber for the purpose of removing coke residue therefrom. If desired, a suitable pipe may be provided through the closure member 24 for the purpose of admitting any desired fluid into the lower part of the coking chamber.

In the lower portion of the tower 15 the heavy entrained tar-like constituents are separated from the vapors by subjecting the latter to a slight condensation. A valved line 25 extends from the base of the fractionating column 15 and may be provided with a pump 26 for the purpose of withdrawing such separated heavy material together with the small amount of heavy condensate admixed therewith. The thus withdrawn material may be passed through branch conduits 27 and/or 28 connecting with the outlet and inlet, respectively, of the heating coil 6. In this manner the heaviest material is returned to the coking chamber 12 wherein it is further decomposed.

The fractionating column 15 may be provided with a suitable drawoff line 29, positioned at a

somewhat elevated point, for the purpose of withdrawing the clean charging stock produced in accordance with this process and which is separated in tower 15 as reflux condensate. As shown in the drawing, the valve line 29 may be positioned so as to withdraw the clean charging stock from a point above the second or third plate within the fractionating column.

In operating, the coking chamber 12 preferably should be preheated to a satisfactory temperature, for example 650° F., in order to prevent the heated residue entering it from cooling to a point below cracking temperature. The preheating of the coking chamber 12 may be accomplished in any suitable manner, such as by passing steam or heated oil therethrough or by combustion therein. After the chamber to be used for coking has been preheated to the desired temperature, the petroleum residue from the source of supply and at a temperature of about 720° F. is forced through the heating coil 6 at a rate sufficient to prevent excessive cracking or coke deposition therein. The residue in passing through the heating coil may be raised to a temperature of about 900° to 910° F. or to such a high temperature that coking thereof may be accomplished in the coking chamber 12 by its contained heat. If desired a small quantity of steam may be forced into the oil to speed its flow through all or a part of the heating coil and minimize cracking conditions therein. The temperature to which the heavy residue is raised in passing through the heating coil may be varied depending upon the heavy residue being treated. For example, for a heavy residue from Mid-Continent crude, the temperature thereof should preferably be above about 870° F. to insure the production of a satisfactory coke without too much volatile matter. Temperatures above about 940° F. for petroleum residue of this character tend to cause excessive coke formation and deposition in the heating coil.

I have found that with additional heat supplied to the thus heated residue, coke and gasoline of superior quality are obtained, together with a maximum yield of clean charging stock. While it is possible to raise the residue to the desired high temperature in the heating coil, it is not practical or economical to do so in view of the adverse coke difficulties always experienced. In accordance with my invention, the residue may be supplied with additional heat before entering the coking chamber while avoiding the disadvantages heretofore present. I accomplish the additional heating of the residue by admitting to the stream thereof, preferably after leaving the heating coil, a regulated quantity of an oxidizing fluid, such as air or other combustion supporting or oxidizing material, to thus raise the temperature of the residue to that desired in its passage through the pipes connecting the heating coil and the coking chamber. As shown in the drawing, a regulated quantity of air or other suitable fluid, preheated if desired, may be forced through a valved line 31, having a suitable nozzle or the like, into the stream of heated oil residue leaving the heating coil. The heat producing reaction which takes place upon the introduction of air or an oxidizing medium into the oil residue is preferably carried out in the pipes before the oil reaches the coking chamber. In this manner the oil is at the desired temperature when entering the coking chamber. The air may be forced into the stream of oil in the direction of flow and a practical way of accomplishing this

introduction of the air may be to arrange the nozzle tangentially to the transfer line 8. The air entering the stream of oil residue consumes a very small quantity of it in supplying the additional heat required to raise the temperature of the stream entering the coking chamber to that desired. For example, the temperature of the oil leaving the heating coil may be raised from 900° F. to 940° F. before entering the 10 coking chamber by adding 160 cubic feet of air at 60° F. per barrel of charge of 50 gallons each. The quantity of air introduced may be varied and it will be clear to those skilled in the art that a controlled supplemental heating of the 15 petroleum residue may be accomplished without any detrimental effects, before it enters the coking chamber.

The thus heated petroleum residue is admitted into the chamber 12 by means of one or more 20 of the pipes 11 and starts coking from the bottom by its own contained heat, until the chamber is substantially full. In operation it may be preferred to supply the heated residue to the lowest pipe 11 as long as possible in order to accomplish 25 the desired building up of the coke from the bottom. If the lowest pipe 11 begins to clog, the heated stream of residue may then be introduced into the next higher pipe 11. By building up the coke in this manner, it is possible to obtain the 30 production of a much denser coke than would be possible if the heated residue was only supplied at one point.

The vapors from the coking chamber entering the fractionating column 15 are therein fractionated to yield an overhead gasoline or pressure distillate which is condensed and collected in the distillate receiver 19. Clean cracking stock is withdrawn through the pipe 29 and the reflux below the lowest two or three plates, which 35 is not sufficiently clean to be raised to a high cracking temperature in that it consists mainly of heavy entrained matter separated from the vapors, is preferably returned by the pipe 25 to the inlet and/or outlet of the heating coil 6. 40 In operating in accordance with my invention it is preferred to maintain the coking chamber 12 at approximately atmospheric pressure. In operating in this manner only sufficient pressure is applied by the pump 3 to force the petroleum 45 residue through the heating coil 6 at the desired rate to prevent coke deposition therein. The destructive distillation taking place in the coking chamber may, if desired, be effected at moderately superatmospheric pressure of between 50 55 to 30 pounds per square inch.

In coking petroleum residues from Mid-Continent crude temperatures between about 870° F. and about 940° F. have been employed. My invention contemplates raising the particular petroleum residue being treated to a temperature just below that at which objectionable coke deposition takes place in the heating coil and thereafter supplying additional heat to the thus heated residue to raise it to a higher temperature. For example, the oil in passing through the heating coil may be raised to a temperature of about 920° F. and thereafter supplied with additional heat to cause the temperature to be raised to about 960° F. 60 It has been found that the coke and gasoline obtained when additional heat is supplied in accordance with my invention possesses superior qualities to those obtained when additional heat is not supplied. The oxidized gasoline obtained is 65 much more stable than finished cracked gasoline as

regards oxidation stability and it has been found that as little as 2½% of oxidized gasoline produced in accordance with my invention when mixed with finished gasoline causes the mixture to be more stable than the finished gasoline alone. 5 Moreover, it has been found that the octane number of the gasoline obtained in accordance with my process was better than that obtained without supplying additional heat by oxidation.

The addition of air can be accomplished without any harmful effect to the transfer line or air nozzle whereas heretofore hot spots or the like were likely to occur when air was introduced. This is particularly true when air is introduced into an enlarged coking chamber, the difficulty 15 residing in the lack of positive indications of combustion within the chamber and the inability to accomplish even distribution of the air throughout the body of oil residue being coked.

Coke obtained in accordance with my invention has been found to be harder than that obtained when operating the process without the introduction of a controlled quantity of air. The coke was not only harder, but also possessed a greater percentage of lumps than was possible 25 heretofore. For example, for one particular operation, it has been found that an increase of 10% of lump coke (as determined by a screen of three inch square mesh) was obtained.

While my invention has been described as coking uncracked petroleum residue obtained from the distillation of crude oil, it is to be understood that such a residue mixed with pressure tar obtained from a cracking operation may also be coked. The pressure tar may be introduced into 35 the stream of petroleum residue passing through the line 4 by means of a valved pipe 32. If desired, the pressure tar may be mixed with the petroleum residue in the source of supply 1 and the mixture forced through the heating coil as 40 described. When pressure tar is mixed with the petroleum residue, it has been found that more advantageous results are obtained when a small quantity of the pressure tar is used. For example, about 7 to 10% of pressure tar may be 45 mixed with the petroleum residue to obtain the desired valuable by-products as well as the desired maximum yield of clean charging stock.

Obviously, many modifications in the apparatus and mode of operation may be made without departing from the spirit of the invention which is defined in its true scope in the appended claims.

What I claim is:

1. A method of converting heavy residual hydrocarbon oil into lower boiling hydrocarbons and a solid coke residue, which comprises passing heavy residual hydrocarbon oil in a confined stream through a heating zone, heating said oil during passage through said zone to a cracking 55 temperature, controlling the rate of flow of said oil through said zone and time of treatment therein to avoid troublesome coke deposits within said heating zone, thereafter introducing a gas containing free oxygen into said stream of heated 60 oil to effect partial combustion of said oil to further increase the temperature thereof, limiting the amount of gas containing free oxygen added to said heated oil to prevent the temperature thereof from rising more than about 40° F. above 65 that obtained in the heating coil and maintaining said oil thus heated in a coking zone for a period adequate to convert said oil into a solid coke residue and lower boiling hydrocarbons.

2. A method of converting heavy residual hy- 75

drocarbon oil into lower boiling hydrocarbons and a solid coke residue, which comprises passing heavy residual hydrocarbon oil in a confined stream through a heating zone, heating said oil during passage through said zone to a cracking temperature, controlling the rate of flow of said oil through said zone and time of treatment therein to avoid troublesome coke deposits within said heating zone, thereafter introducing a gas containing free oxygen into said stream of heated oil to effect partial combustion of said oil to further increase the temperature thereof, limiting the amount of gas containing free oxygen added to said heated oil to prevent the temperature thereof from rising more than about 40° F. above that obtained in the heating coil, thereafter passing said heated oil into an enlarged coking chamber, maintaining said oil within said coking chamber for a period adequate to convert said oil into a solid coke residue and hydrocarbons boiling below said heavy residual oil.

3. A method of processing heavy hydrocarbon oil to produce gasoline which comprises passing

said oil in a confined stream through a tubular heating coil, heating said oil during its passage through said coil to cracking temperature, controlling the temperature and time of treatment of the oil within said coil with respect to each other to effect the maximum cracking of the oil within the coil while avoiding troublesome coke deposits therein, passing the converted products from said heating coil into a reaction zone wherein further conversion is effected and vapors separate from residue, introducing air into the cracked products from said tubular heating coil in an amount of about 3.2 cubic feet of air at 60° F. for each gallon of oil treated to further heat said oil by partial combustion thereof to a temperature not more than about 40° F. above that obtained in the heating coil, separately removing the vapors from said reaction zone and subjecting them to fractionation to separate a gasoline distillate fraction relatively free of gum-forming constituents.

MARVIN C. ROGERS.
